HARRY NYQUIST, OF JACKSON HEIGHTS, NEW YORK, ASSIGNOR TO AMERICAN TELEPHONE AND TELEGRAPH COMPANY, A CORPORATION OF NEW YORK.

ARRANGEMENT FOR INCREASING THE POWER OF REPEATER CIRCUITS.

Application filed August 26, 1924. Serial No. 734,341.

This invention relates to repeater circuits and more particularly to arrangements for increasing the output power of the amplifiers employed in repeater circuits.

In a repeater circuit of the 22 type it has been proposed to increase the output power of each amplifier by making the impedance of the load into which the amplifier works greater than the internal impedance of the amplifier. Where no filter is employed in the repeater circuit this may be readily accomplished without disturbing the passive impedance of the repeater as viewed from the line to which it is connected, by changing the ratio of transformation between the output circuit of the amplifier and the line to which it is connected, at the same time making a compensating change in the input impedance of the amplifier in the repeater path transmitting in the opposite direction. Where, however, a filter is employed in the amplifier circuit, the problem of increasing the load impedance is complicated by the presence of the filter and it becomes necessary to treat the circuits in a somewhat different manner. It is one of the objects of the present invention to provide an arrangement for the solution of this problem which will enable the employment of filters in the amplifier circuit and at the same time will permit of maintaining the passive impedance of the repeater at any desired value.

Other and further objects of the invention will be clear from the detailed description thereof when read in connection with the accompanying drawing, Figure 1 of which shows a simplified diagram of a portion of a 22 repeater circuit in which no filters are employed, Fig. 2 of which is a similar diagram showing a filter in the output circuit of the amplifier, and Fig. 3 of which is a simplified circuit diagram of a 22 repeater employing the arrangements of the present invention.

Referring to Fig. 1, L designates a transmission line associated by means of a hybrid coil 10 with the input side of an amplifier AE and with the output side of an amplifier AW, the line L being balanced by the usual network N in order that the two paths of

the 22 repeater may be substantially conjugate. In such circuits the impedance Z_1 , looking into the line L, should be equal to the impedance Z_2 looking into the balancing network N in order that the repeater will be properly balanced. In order to avoid reflection losses, the passive impedance Z_1' , looking from the line into the 22 repeater, should be equal to the impedance of the line Z_1 . Similarly, the impedance Z_2' , looking from the balancing network towards the hybrid coil, should be equal to the impedance Z_2 of the balancing network. It has been found that the passive impedance Z_1' will be equal to the impedance Z_1 of the line if the internal impedance Z_4 of the output circuit of the tube AW be made equal to the load impedance Z_4' and if the input impedance Z_3 of the amplifier AE be made equal to the impedance Z_3' looking into the hybrid coil.

In circuits such as shown in Fig. 1, the power in the output circuit of a tube such as AW may be expressed as

$$I^2(R_4 + R_4')$$

where I is the output current, R_4 is the real part of Z_4 , the internal impedance of the tube, and R_4' is the real part of Z_4' , the load impedance. It is, of course, desirable that the circuit be so designed that the maximum power be consumed in the load, and the power thus consumed may be expressed as I^2R_4' . For a given voltage the power consumed in the load will be a maximum when the internal impedance Z_4 of the tube is the conjugate of the load impedance Z_4' , provided there is nothing to limit the current. In the case of the vacuum tube, however, the current is limited by saturation and if we should increase the applied voltage the current I would not be further increased after reaching the saturation point. Therefore, in order to increase the power consumed by the load we may increase the load impedance Z_4' so that it becomes greater than the internal impedance Z_4 of the tube, at the same time increasing the voltage to keep the current at a maximum.

In the case of a simple circuit such as

that shown in Fig. 1, the increase in the load impedance Z_4 may be readily provided for by changing the ratio of the primary to the secondary winding of the transformer 10 so as to step up the impedance of the line and artificial line as seen through the transformer. This will, of course, produce a change in the passive impedance Z_1' of the repeater but may be compensated for by 15 correspondingly increasing the impedance Z_3 or, in other words, increasing the impedance of the potentiometer 11 so as to bring the passive impedance of the repeater back to equality with the impedance Z_1 of the 20 line.

Where a filter such as F is provided in the output circuit of the amplifier as shown in Fig. 2 the problem is not so simple. The impedance-frequency characteristic of the 25 filter F will not, in general, be a smooth curve but will be irregular and will only be smooth in case its characteristic impedance Z_4' as viewed from the tube AW is equal to the impedance Z_4 of the tube. If 30 we make the impedance looking into the filter larger than the tube impedance in order to increase the power, the impedance of the filter will be irregular and compensating irregularities would necessarily have to 35 be introduced in the input circuit of the tube A₂ in order to have the passive impedance Z_1' a smooth curve. By the present invention the power is increased by making the impedance of the output circuit of the tube 40 larger than the internal impedance of the tube, thus introducing irregularities in the filter impedance, but these irregularities are compensated for by introducing a filter element having compensating irregularities in 45 the input circuit of the tube transmitting in the opposite direction. As a consequence, the passive impedance Z_1' will be a smooth curve by reason of the fact that the irregularities introduced in the transmitting branch will be compensated for by irregularities introduced in the receiving branch.

In order to understand how this result is obtained, a theoretical discussion will now be given. It may readily be shown that the 50 passive impedance Z_1' of a repeater such as that shown in Fig. 1, for example, equals

$$Z_1' = \frac{Z_2 Z_3 + \frac{Z_2 Z_4 + Z_3 Z_4}{4n^2}}{Z_2 + Z_3 + \frac{Z_4}{4n^2}} \quad (1)$$

where Z_2 is the impedance of the balancing network, Z_3 is the impedance of the input of the repeater element, i. e., the impedance of the potentiometer, Z_4 is the impedance of the output of the repeater element i. e., the tube or tube with filter, and n is the ratio of turns on the output transformer in the plate circuit to the total number on all the other windings. As has been previously

stated, the passive impedance Z_1' should be equal to the impedance Z_1 of the line, and the impedance of the line should equal the impedance Z_2 of the network N. Consequently, the passive impedance Z_1' should equal the impedance Z_2 of the network. Introducing the condition that the passive impedance and the network impedances are equal, and each are made equal to, say, Z , the relation between the impedances as expressed by equation (1) becomes

$$Z^2 = \frac{Z_3 Z_4}{n^2} \quad (2)$$

For simplicity in computation, we will next make $Z^2 n^2 = a^2$. The relation between the impedances then becomes

$$a^2 = Z_3 Z_4 \quad (3)$$

or putting

$$Z_3 = \frac{1}{Y_3} \quad (4)$$

we have

$$a Y_3 = \frac{Z_4}{a} \quad (5)$$

for the relation between the impedances.

Expressed in words, relation 5 is that the passive impedance of the repeater will be perfect at all frequencies (that is, will be equal to the line impedance Z_1 at all frequencies), provided that the admittance of the input of the repeater element multiplied by a is equal to the impedance of the output divided by a at all frequencies. This can readily be accomplished by providing in the input a network or filter so constructed as to be, element for element, the counterpart of the network in the output, series impedances in one case being made to correspond to bridged admittances in the other, series coils being made to correspond to bridged condensers, series condensers being made to correspond to shunt coils, and series resistances being made to correspond to bridged conductances. In particular, if the network in the output circuit as shown at N₂ in Fig. 3 is a low pass filter terminating in mid-shunt sections, the corresponding network N₁ in the input will be another low pass filter having the same cut-off frequency but terminating in mid-series sections. More specifically, if the characteristic impedance Z_6 of the filter in the output is made equal to the impedance Z_6' of the line and network as they appear from the filter, the impedance Z_5 of the filter in the input will be equal to the impedance Z_5' of the line and network as viewed from the tube. The above relation is hereinafter referred to as a reciprocal relation.

Heretofore the filter in either the output circuit or the input circuit of the amplifier (where no attempt is made to in-

- crease the power by increasing the load impedance) consists of two sections of a low pass filter. In accordance with the present invention, however, one section will be sufficient in the output because of the fact that there will be another section N_1 (not shown) in the input of the same amplifier. The output section could be made up as illustrated of a series coil and two bridged condensers. 5
- 10 The section in the input would then be made up of a bridged condenser and two series coils, making a total of three coils and three condensers per repeater element instead of two coils and three condensers, as shown in 15 Fig. 2. In other words, the amount of equipment would only be increased by one coil, notwithstanding that the load power may be increased as desired by placing the two filter sections one in the input and one 20 in the output as illustrated.

As has already been stated, if we provide a filter in the output only, its impedance will not be smooth unless its characteristic impedance as viewed from the tube is equal 25 to the tube impedance. By splitting the filter, however, the impedance of the one section may be increased to increase the power consumed in the load and the irregularities thus introduced will be compensated for by corresponding irregularities of 30 the filter section in the input. It will be understood, of course, that the two filter sections will be so chosen as to have the same critical frequency.

35 It will be apparent that with this arrangement the passive impedance of the filter is correct not only in the range for which the filter transmits freely but for every frequency whatever. This is a matter of considerable importance as it improves the passive impedance of the repeater in the neighborhood of the cut-off frequency.

40 It will be obvious that the general principles herein disclosed may be embodied in many other organizations widely different from those illustrated without departing from the spirit of the invention as defined in the following claims.

45 What is claimed is:

50 1. In a signaling circuit, an amplifier, a network associated with said amplifier, said network comprising two units, one unit being included in the input circuit of the amplifier and the other in the output circuit, the impedance-frequency curve of the one unit being proportional to the reciprocal of that of the other.

55 2. In a signaling system, an amplifier, a network associated therewith, said network comprising two units, one in the input circuit of the filter and the other in the output circuit, said units comprising series and shunt elements, the elements of the two units being so related to each other that for 60 each unit a series impedance in one will cor-

respond to a bridged admittance in the other.

3. In a signaling system, an amplifier, a network associated therewith comprising two units, one unit being arranged in the input circuit of the amplifier and the other in the output circuit thereof, each of said units comprising series and shunt impedances, one of which is an inductance and the other of which is a capacity, the elements of the two units being so related to each other that the series coil of the one corresponds to a bridged condenser in the other. 70

4. In a signaling system, an amplifier, a filter associated therewith comprising two sections, one section being arranged in the input circuit of the amplifier and the other in the output circuit thereof, one of said sections terminating in mid-shunt and the other terminating in mid-series. 80

5. In a signaling circuit, an amplifier, a filter associated therewith, said filter comprising two sections, one arranged in the input circuit and the other in the output circuit of the amplifier, each filter comprising series and shunt impedances, one of which is an inductance and the other of which is a capacity, the impedance elements of the two sections being so related to each other that a series inductance in the one corresponds to the bridged condenser in the other, one of said filters terminating in mid-series and the other in mid-shunt. 90

6. In a 22-repeater circuit having an amplifier in each path, a filter unit in the output circuit of the amplifier in one path, a second filter unit in the input circuit of the amplifier in the other path, the impedance-frequency characteristic of the one unit being proportional to the reciprocal of that of the other. 100

7. In a 22-repeater circuit having an amplifier in each path thereof, a filter unit included in the output circuit of the amplifier in one path, and another filter unit included in the input circuit of the amplifier in the other path, the impedance looking into said first mentioned filter unit being greater than the internal impedance of the amplifier, and the impedance-frequency curve of the other unit being proportional to the reciprocal of that of said first unit. 110

8. In a 22-repeater circuit having an amplifier in each path thereof, a filter unit in the output circuit of one amplifier and another filter unit in the input circuit of the other amplifier, said filter units being so related to each other that series impedances in the one will correspond to bridged admittances in the other. 120

9. In a 22-repeater circuit having an amplifier in each path thereof, a filter unit in the output circuit of the amplifier of one path and another filter unit in the input circuit of the amplifier of the other path, 130

- each of said units comprising series and shunt impedance elements, one of which is an inductance and the other of which is a capacity, the elements of the two filter units being so related to each other that the series inductance of the one corresponds to a bridged capacity of the other. 5
10. In a 22-repeater circuit having an amplifier in each path thereof, a filter unit in the output circuit of the amplifier of one path and another filter unit in the input circuit of the amplifier of the other path, each of said units comprising series and shunt impedance elements, one of which is a capacity, the elements of the two filter units being so related to each other that the series inductance of the one corresponds to a bridged capacity of the other, and a series 15 capacity of the one corresponds to a shunt inductance of the other. 20
11. In a 22-repeater circuit having an amplifier in each path thereof, a filter section in the output circuit of the amplifier of one path and another filter section in the input circuit of the amplifier of the other path, each of said filter sections comprising series and shunt impedance elements, and one of said filter sections terminating in mid-shunt 25 and the other section terminating in mid-series. 30
12. In a 22-repeater circuit having an amplifier in each path thereof, a filter section in the output circuit of the amplifier of one path and another filter section in the input circuit of the amplifier of the other path, each of said filter sections comprising series and shunt impedance elements, one of which is an inductance and the other a capacity, 35 the elements of the two filter sections being so related to each other that a series inductance in one corresponds to a bridged capacity in the other and a series capacity in one corresponds to a shunt inductance in the 40 other, one of said sections terminating in mid-series and the other in mid-shunt. 45
13. In a signaling system, a transmission circuit having branches, filter units in each of said branches, the impedance frequency 50 curve of one of said filter units being proportional to the reciprocal of that of the other. 55
14. In a signaling system, a transmission circuit having branches, filter units in each of said branches, said filter units comprising series and shunt elements, the elements of the two units being so related to each other that for each unit a series impedance in one will correspond to a bridged admittance in the other. 60
15. In a signaling system, a transmission circuit having branches, filter units in each of said branches, each of said units comprising series and shunt impedances, one of 65 which is an inductance and the other of which is a capacity, the elements of the two units being so related to each other that a series coil of the one corresponds to a bridged condenser of the other and a series condenser of one corresponds to a shunt coil of the other. 70
16. In a signaling system, a transmission circuit having branches, a filter network in each branch, one of said filter networks terminating in midshunt and the other terminating in midseries. 75
17. In a signaling system, a transmission circuit, a band filter for transmitting with negligible attenuation a band of frequencies while attenuating frequencies lying outside of the band, a connection between said filter and said circuit, said filter comprising complementary units each transmitting the same range of frequencies, and the impedance frequency curve of the one unit being proportional to the reciprocal of that of the other, so that the impedance of the combination will be substantially constant at all frequencies either within or without the band of free transmission. 80 85 90
18. In a signaling system, a transmission circuit, a band filter for transmitting with negligible attenuation a band of frequencies while attenuating frequencies lying outside of the band, a connection between said filter and said circuit, said filter comprising complementary units each transmitting the same range of frequencies, and each unit comprising series and shunt elements so related to each other that for each unit a series impedance in one will correspond to a bridged admittance in the other whereby the impedance of the combination will be substantially constant at all frequencies either within or without the range of free transmission. 95 100 105
19. In a signaling system, a transmission circuit, a band filter for transmitting with negligible attenuation a band of frequencies while attenuating frequencies lying outside of the band, a connection between said filter and said circuit, said filter comprising complementary units each transmitting the same range of frequencies, each of said units comprising series and shunt impedances, one of which is an inductance and the other of which is a capacity, the elements of the two units being so related to each other that a series coil in the one corresponds to a bridged condenser in the other and a series condenser of one corresponds to a shunt coil of the other whereby the impedance of the combination will be substantially constant at all frequencies either within or without the range of free transmission. 110 115 120
20. In a signaling system, a transmission circuit, a band filter for transmitting with negligible attenuation a band of frequencies while attenuating frequencies lying outside 125

of the band a connection between said filter and said circuit, said filter comprising complementary units each transmitting the same range of frequencies, one of said units terminating in midshunt and the other unit

5 substantially constant at all frequencies either with-
in or without the range of free transmission.

In testimony whereof, I have signed my 10
name to this specification this 21st day of
August, 1924.

HARRY NYQUIST.
